Emile Storer Atty.

UNITED STATES PATENT OFFICE.

CHARLES A. MARIEN, OF ST. LOUIS, MISSOURI.

AUTOMOBILE-RADIATOR.

1,391,486.

Specification of Letters Patent. Patented Sept. 20, 1921.

Application filed December 8, 1919. Serial No. 343,290.

To all whom it may concern:

Be it known that I, CHARLES A. MARIEN, a citizen of the United States, residing at St. Louis, State of Missouri, have invented 5 certain new and useful Improvements in Automobile-Radiators, of which the following is a full, clear, and exact description, reference being had to the accompanying drawings, forming a part hereof.

10 The present invention is directed to improvements in automobile radiators, the object sought being to provide a radiator with a core demountable as a unit from the outer frame which is secured to the body of the 15 vehicle, whereby the same may be readily repaired and any leaks stopped without inconvenience to the operator, the demountable character of the core permitting of ready access to the engine when the operator 20 desires to work on the same, without necessitating the removal of the entire radiator as is the case where the outer frame and core are integral. A further object is to provide a radiator in which the core may 25 be attached to the frame without the use of bolts and nuts, thereby saving additional time when occasion arises to make repairs. The present improvement presents further and other advantages the character 30 of which will be more fully apparent from the following detailed description in connection with the accompanying drawings in which—

Figure 1 represents a front elevation of 35 one form of my improved radiator; Fig. 2 is a vertical cross-section on the zig-zag line 2—2 of Fig. 1, one of the sealing plates being shown withdrawn from normal position; Fig. 3 is a top plan view; Fig. 4 is a 40 detached perspective of one of the sealing plates with its circulating goose-neck; and Fig. 5 is a perspective of a modified construction of radiator.

Referring to the drawings, and for the 45 present to Figs. 1 to 4 inclusive, 1, represents the outer frame provided with top and bottom hollow compartments or circulating tanks t , t' , respectively, the upper tank serving as the intake and the lower 50 tank as the discharge for the circulating cooling medium (water), the rear wall of the tank t being tapped by the feed pipe 2 and the corresponding wall of the tank t' being tapped by the discharge pipe 3 leading from the engine as well understood in 55 the art. The core-body C is herein shown

as of the conventional cellular type, the same terminating in the top and bottom circulating heads 4 and 4' respectively. The core (the body C with its heads 4, 4') 60 is insertible into, and demountable from, the outer frame as a unit, suitable provision being made to secure the core to the frame and at the same time establish circulating intercommunication between them when 65 the core has been fully inserted into the frame. To facilitate insertion of the core into the frame the inner walls of the tanks t , t' , are made slightly sloping as shown in Fig. 2, the core being limited in its inward 70 movement into the frame by the grooved ribs 5, 5, disposed in pairs along the front walls of the heads 4, 4', the said ribs projecting outwardly beyond the faces of the 75 heads so as to engage the outer faces of the front walls of the tanks t , t' , when the core is fully inserted into the frame. The front walls of the tanks t , t' , are provided with corresponding grooved ribs 5', 5', which when the parts are assembled aline with the 80 ribs 5, 5, of the core-heads, the two sets of ribs forming suitable grooves or ways w for the reception of a sealing plate 6 preferably provided on its inner face with a packing sheet or gasket 7, the said plates having 85 formed thereon (or secured thereto) the goosenecks or circulating bends 8, the opposite ends of the passageways whereof are free to communicate through the plates with the tanks t , t' , and heads 4, 4'. The 90 length of a plate 6 is such as to extend across the front walls of the frame tank and core-head at either end of the radiator, the gooseneck on the plate spanning the seam or joint 95 h between the tank and head, one end of the gooseneck communicating with the tank through an opening o in the front wall thereof, and the opposite end communicating with the core head through an opening o' in the front wall of said head, the distance 100 between the gooseneck terminals (corresponding to the distance between a pair of openings o , o'), being such as to leave a sufficient length of imperforate portion of the plate between said terminals to permit the 105 imperforate portions of the plates to cover the openings o in the frame tanks when the plates are withdrawn sufficiently to permit the core to be removed from the frame. In other words, by pulling out the plates 6 110 sufficiently to bring their inner ends even with the inner edges of the outer faces of

the front walls of the tanks t , t' , the core is free to be removed from the frame, any escape of water from the tanks of the frame being prevented by the imperforate portions of the plates between the goose-neck terminals covering the openings o , o' , of said tanks. The demounting of the core is consequently attended with practically no loss of water from the outer frame, the sealing plates closing the openings through which the water would otherwise escape. In Fig. 2 one of the sealing plates is shown withdrawn to proper position to release the core, in which position it likewise covers the opening o in the tank t of the outer frame. In practice a very slight inward taper is imparted to the ribs 5 , $5'$, so that the grooves w which receive the sealing plate converge toward the center of the frame. A corresponding taper is necessarily given to the sides of the sealing plate so that when the same is inserted into the ways it will become firmly wedged when driven home the full distance, after which it is prevented from working loose by an ordinary latch 9 pivoted to the top and bottom walls of the tanks t , t' , respectively, and turned to engage the outer end of the sealing plate (Fig. 3). To remove the plates, the latches are first turned to releasing position, the plates are given a tap with a hammer or other tool applied to the inner ends thereof so as to start the plates outwardly, after which the operator by seizing the goose-necks may withdraw the plates sufficiently to clear the heads of the core, permitting the latter to be withdrawn from the frame (see dotted position of core in Fig. 2). The plates in their partly withdrawn position keep the openings o , o' , covered as previously described, thus preventing the escape of water from the frame tanks.

In the form above described, the sealing plates with their goose-necks are directly opposite the feed and discharge pipes 2, and 3, respectively. The construction may however be modified so as to have a sealing plate and goose-neck on either side of the pipes aforesaid, the latter arrangement preventing any likelihood of short-circuits between the feed and discharge pipes and the goose-necks, and insuring a proper diffusion of the water in the frame tanks and core heads so as to insure at the same time an even temperature in the water body along any given horizontal plane. Such a modified construction is shown in Fig. 5. In this modification too, are shown sealing plates 6' the inner ends of which extend farther beyond the goose-necks than do their outer ends, the said inner extensions being availed of to cover the openings o , o' , of the frame tanks when the plates are partially withdrawn to allow for the removal of the core. In the modified construction

the openings o , o' , are so spaced that the imperforate portion of the sealing plate between the goose-neck terminals is not available to cover the opening o with a partial withdrawal of the plate, making it necessary to depend on the inner imperforate extension as clearly shown in Fig. 5. The core may for convenience be provided with hand holes 10 for purposes of handling the same. In the modified construction the outer frame and core are the same as in the first form described and are accordingly identified by the same reference numerals. The operation of the modified structure in Fig. 5 is obvious from the drawings and requires no further description. In both forms the core is demountable as a unit, and may be not only quickly detached from, but as quickly restored to the outer frame, without the use of stud-bolts and nuts, thereby resulting in a very simple construction. The radiator is of course susceptible of further and other changes and modifications without involving a departure from the nature or spirit of the invention.

Having described my invention what I claim is:

1. In a radiator, an outer frame provided with suitable compartments or tanks for the circulation of a cooling medium, a detachable core inserted in said frame, and means detachable from said frame and core and spanning the joint between the same for fastening the core to the frame and simultaneously establishing communication between the core and circulating tanks of the frame.

2. In a radiator, an outer frame provided with suitable compartments or tanks for the circulation of a cooling medium, a detachable core terminating in circulating heads adapted to be brought in juxtaposition with the tanks aforesaid, and means detachable from said frame and core and spanning the joint between the same for securing the heads of the core to the tanks of the frame and simultaneously establishing communication between the core heads and frame tanks.

3. In a radiator, an outer frame provided with suitable compartments or tanks for the circulation of a cooling medium, a detachable core terminating in circulating heads adjacent to said tanks, groove formations on the face walls of the heads and tanks alined across the joints between the heads and tanks, and sealing plates provided with circulating bends insertible in said grooves for securing the core to the frame, the said bends spanning the joints aforesaid and establishing communication between the frame tanks and core heads.

4. In combination with a radiator provided with an outer fluid circulating frame

and an inner demountable circulating core, a sealing plate provided with a hollow goose-neck having its terminals within the confines of the plate and opening through the 5 plate into the frame and core respectively.

5. In a radiator, an outer frame having top and bottom circulating tanks provided with openings in one of the face walls thereof, a demountable core in said frame terminating in top and bottom circulating heads 10 adjacent the tanks aforesaid, said heads being provided with openings in the corresponding walls with the walls of the tanks, grooved ribs on the core heads disposed on 15 either side of the openings in the heads and projecting beyond the heads to engage the adjacent walls of the tanks, grooved ribs formed on the tank walls engaged by the 20 ribs of the core heads and alining therewith upon assembling of the parts and thereby forming continuous ways across the joints between the core heads and frame tanks, and sealing plates insertible in said ways for securing the core to the frame, the said 25 plates being provided with circulating passage-ways spanning the joints aforesaid, and communicating with the core heads and frame tanks through the openings in the face walls thereof aforesaid.

30 6. In a radiator, an outer fluid circulating frame, an inner core forming joints with the inner walls of the frame, sealing plates slideable across the joints and establishing intercommunication between the core and

frame, and suitable latches on the frame for 35 fastening the sealing plates.

7. In a radiator, an outer frame provided with suitable circulating compartments or tanks, a detachable core inserted in said frame and terminating in circulating heads 40 45 brought into juxtaposition with the tanks, the said tanks and heads being provided with openings in adjacent walls, sealing plates provided with circulating bends or passage-ways operating in one position to secure the core to the frame and establish communication between the tanks and heads through the openings aforesaid, said plates being provided with imperforate portions 50 for covering the openings in the tank walls when shifted to a position to release the core from the outer frame.

8. In a radiator provided with an outer fluid circulating frame and an inner demountable core, a movable connecting member 55 operating to establish communication between them for one position of said member, and to cut off said communication and at the same time release the core from the outer frame with another position of said 60 member.

In testimony whereof I affix my signature, in presence of two witnesses.

CHAS. A. MARIEN.
